ELECTRONIC ORGAN

Victor Harold Ward and Rhodam George Waters
Hewitt, Chorleywood, England

Application July 8, 1952, Serial No. 20,519
In Great Britain March 6, 1952

Term of patent 14 years

(Cl. D56—1)

To all whom it may concern:

Be it known that we, Victor Harold Ward, a citizen of Great Britain, residing at Le Vallon, Lower Road, Chorleywood, Hertfordshire, England, and Rhodam George Waters Hewitt, a citizen of Great Britain, residing at Holly Tree House, Herongate Road, Chorleywood, Hertfordshire, England, have jointly invented a new, original, and ornamental Design for an Electronic Organ, of which the following is a specification, reference being had to the accompanying drawings, forming a part hereof.

Fig. 1 is a front perspective view of an electronic organ, showing our new design.

Fig. 2 is a rear perspective view of the organ.

We claim:

The ornamental design for an electronic organ, as shown.

VICTOR HAROLD WARD.
RHODAM GEORGE WATERS HEWITT.
